UNITED STATES PATENT OFFICE.

FRANCIS L. CLARK, OF PITTSBURG, PENNSYLVANIA, ASSIGNOR TO THE AMERICAN BRAKE COMPANY, OF ST. LOUIS, MISSOURI, A CORPORATION OF MISSOURI.

BRAKE SLACK-ADJUSTER.

SPECIFICATION forming part of Letters Patent No. 760,778, dated May 24, 1904.

Application filed September 6, 1901. Serial No. 74,536. (No model.)

To all whom it may concern:

Be it known that I, FRANCIS L. CLARK, a citizen of the United States, residing at Pittsburg, county of Allegheny, State of Pennsylvania, have invented or discovered a certain new and useful Improvement in Brake Slack-Adjusters, of which improvement the following is a specification.

My invention relates to slack-adjusting mechanism for railway-brakes, and has for its object to provide an adjustable connection between the piston of a fluid-pressure brake-cylinder and brake-rigging whereby the slack of said brake-rigging, due to the wear of the brake-shoes, stretching of the rigging, or other causes, may be automatically taken up, so as to preserve a uniform travel of the brake-piston.

My invention comprises an extensible push-bar made in sections having a sliding ratchet connection, the end of one section being adapted to operate loosely in the ordinary hollow piston-rod of the brake-cylinder and the other section being connected to a brake-operating lever.

It also includes a spring which is secured to a stationary or fixed support and adapted to be operated by an excessive travel of the brake-piston, so that upon release of the brakes the spring will effect a relative movement of the sections of the push-bar.

Other features of my invention will appear hereinafter as the construction is more fully described.

In the accompanying drawings, which illustrate an embodiment of my invention, Figure 1 is a vertical longitudinal section of my improvement shown applied to the rear end of a brake-cylinder. Fig. 2 is a view showing the brake-cylinder in plan and the push-bar in horizontal section. Fig. 3 is a transverse section taken on the line $x-x$ of Fig. 1. Fig. 4 is a transverse section taken on the line $y-y$ of Fig. 2; and Fig. 5 is a rear end elevation of the brake-cylinder, the push-bar being shown in section.

My improvement is particularly adapted to be used in connection with that form of brake-

cylinder in which the piston is provided with a hollow or tubular piston-rod extending 50 through the rear head of the brake-cylinder and adapted to receive the loose push-bar of the brake-rigging, which construction is that now ordinarily employed on freight-cars.

Referring now to the drawings, the piston 55 of the brake-cylinder 1 is provided with the tubular rod 2, extending out through the rear head of the cylinder, and in this is inserted the inner end of one section, 3, of the extensible push-bar, the other section, 10, of which 60 is adapted to be pivotally connected to the lever of the brake-rigging. The push-bar may be constructed with any adjustable sliding connection between the sections; but as a preferred arrangement I have shown the outer 65 end of section 3 extending into a hollow portion of the section 10, forming a sort of telescopic connection, this portion of section 3 being provided with ratchet-teeth 11, adapted to be engaged by pawls 13, pivoted on pins 70 12 in side openings 15 of the outer section 10 of the push-bar. In the construction as shown there are two pawls engaging teeth on opposite sides of the ratchet-bar; but it is obvious that one or any number of pawls may be 75 used, as desired. Springs 14 keep the pawls normally in engagement with the teeth of the ratchet-bar.

On the cylinder-head is bolted or otherwise secured the casing 5, containing a rod 7, having a head 8, and a spring 6, acting between the head 8 of the rod and the opposite end of the casing. The rod 7 extends out through an opening in the casing and loosely through an opening in an arm 4, carried by the section 85 3 of the push-bar, and is provided with adjustable nuts 9 at a suitable distance from the brake-cylinder. The nuts 9 are adjusted at such position on the rod 7 that the arm 4 will not engage therewith during the normal travel 90 of the brake-piston, but when, owing to wear of the brake-shoes or other causes, the piston makes a longer stroke than normal the arm 4 will strike against the nuts 9 and carry the rod along with the push-bar until the brakes 95 are set. This movement will operate to com-

press the spring 6 between the head 8 and the opposite end of the casing 5. Then when the brakes are released and the brake-piston spring moves the hollow piston-rod 2 back toward its release position a slight distance in advance of the following push-bar the spring 6 will have an opportunity to expand and carry the head 8 against the end of its casing. At the same time, since the nuts 9 are bearing against the arm 4, this movement will cause the section 3 of the push-bar to move inward more rapidly than the section 10 is moved back by the relaxation of the brake-rigging, and thus the ratchet-bar will be carried over the pawls one or more notches, according to the extent of the excessive travel of the brake-piston. By this means the push-bar is automatically elongated and the slack of the brake-rigging eliminated.

It will be evident that various other arrangements of the actuating-spring 6 may be used; also, that it may be secured to a fixed part of the car body or frame instead of the brake-cylinder; but I prefer the construction shown, as it renders the operation of the spring more certain and accurate and protects the same from injury.

Having now described my invention, what I claim as new, and desire to secure by Letters Patent, is—

- 30 1. In a brake slack-adjuster, the combination with an extensible push-bar formed of adjustable sections having a sliding ratchet connection, of a spring operating between a fixed support and one section of the push-bar.
- 35 2. In a brake slack-adjuster, the combination with an extensible push-bar formed of adjustable sections, of a spring separate from that of the brake-piston normally bearing on a fixed support and adapted to cause a relative movement of said sections.
- 40 3. In a brake slack-adjuster, the combination with an extensible push-bar formed of adjustable sections, of a spring secured to the exterior of the brake-cylinder and adapted to cause a relative movement of the sections.
- 45 4. In a brake slack-adjuster, the combination of an extensible push-bar formed of adjustable sections, and a spring adapted to be compressed between a fixed support on the

brake-cylinder and one of the adjustable sections when the travel of the brake-piston is excessive.

5. In a brake slack-adjuster, the combination with an extensible push-bar formed of adjustable sections, of a spring for causing a relative movement of said sections and having a fixed support, and means connected to one of said adjustable sections for imparting a stress to the spring when the travel of the brake-piston is excessive. 55

6. In a brake slack-adjuster, the combination with an extensible push-bar formed of adjustable sections, of a spring for causing a relative movement of said sections and having a fixed support on the brake-cylinder, and means connected to one of said adjustable sections for giving a stress to said spring when the travel of the brake-piston is greater than normal. 65

7. In a brake slack-adjuster, the combination of an extensible push-bar formed of adjustable sections, a spring-actuated rod supported by the brake-cylinder and having adjustable nuts, and an arm carried by one of the adjustable sections of the push-bar for engaging said nuts upon an excessive travel of the brake-piston. 70

8. In a brake slack-adjuster, the combination with an extensible push-bar formed of adjustable sections, of a spring-actuated rod having adjustable nuts, a casing for said spring secured to the brake-cylinder head, and an arm carried by one section of the push-bar for engaging said nuts when the travel of the brake-piston is excessive. 80

9. In a brake slack-adjuster, an extensible push-bar formed of adjustable sections having a sliding ratchet connection, two pawls pivoted on one section and engaging teeth on opposite sides of the ratchet-bar of the other section, and a spring for causing a relative movement between said sections. 90

In testimony whereof I have hereunto set my hand.

FRANCIS L. CLARK.
